M. GOLDSTONE.
BURGLAR ALARM.
APPLICATION FILED OCT. 8, 1919.

1,377,198.

Patented May 10, 1921.

*Inventor
May Goldstone
By George E. May*

UNITED STATES PATENT OFFICE.

MAX GOLDSSTONE, OF NEW HAVEN, CONNECTICUT.

BURGLAR-ALARM.

1,377,198.

Specification of Letters Patent. Patented May 10, 1921.

Application filed October 8, 1919. Serial No. 329,200.

To all whom it may concern:

Be it known that I, MAX GOLDSSTONE, a citizen of the United States, residing at New Haven, in the county of New Haven and State of Connecticut, have invented certain new and useful Improvements in Burglar-Alarms, of which the following is a specification, reference being had therein to the accompanying drawings.

10 My invention relates to new and useful improvements in burglar alarms, and has particular reference to that type of alarm that is attached to a door.

It is the object of this invention, among 15 other things, to provide a device of this character that may be readily attached to and supported by the door that will sound an alarm upon the turning of the knob, that will continue sounding until the knob is 20 released; and further, to so design and construct the mechanism of the device that it may be manufactured at the minimum cost and require little or no skill in its attachment.

25 To these, and other ends, my invention consists in the burglar alarm, having certain details of construction and combinations of parts, as will be hereinafter described and more particularly pointed out in the claims.

30 Referring to the drawings, in which like numerals of reference designate like parts in the several figures;

Figure 1 is a side elevation of my improved invention in operative relation to a 35 door which with the door knobs therein is shown in broken lines;

Fig. 2 is a front elevation thereof with the bell mechanism removed; and

Fig. 3 is a view showing a modification of 40 the means for attachment to the knob.

In the embodiment of my invention I provide a base member 10, having in one edge thereof companion slots 12, through which project the screws 11 by which said base 45 plate is secured to the door. By the use of the slots 12 the screws 11 can remain permanently in the door and the device readily detached therefrom by merely loosening the screws. Holes for the screws 50 to pass through the base plate may be substituted for the slots 12, if desired.

Fixed to the base member 10, is a bracket 13 having laterally projecting parallel arms 14 thereon at opposite ends thereof. The 55 base member 10 and bracket 13 may be made integral within my invention.

The numeral 15 designates the carrier, which is supported in the bracket 13 and having a shank 16 at one end that passes through the upper arm 14, an offset portion 60 18 near its lower end and a lug 19 adjacent thereto.

By means of the nut 17 threaded on the shank 16, the vertical position of the carrier 15 in relation to the base member 10 is variable, the spring 20 resisting the action of 65 the nut 17 and keeping the carrier 15 in its then lowermost position.

Fixed to the carrier 15 by the screw 21 is the plate 22 having slots 23 therein similar 70 to the slots 12 and through which project the screws 24 that are threaded into the bell plate 25 secured to the bell 26. By means of the screws 24 and slots 23 the bell may be readily attached to and detached from 75 the plate 22.

The bell 26 having a plunger 27 with a head 28 thereon provides the pushing means and is of the ordinary type and constitutes 80 no part of my invention.

Pivotedly mounted on the lower end of the carrier 15 by the pintle 29 is the lever 30 that is connected at its inner end with the lug 19 by a spring 31 and to the door knob by the chain 32, spring 33 and radial post 85 34. This radial post may be secured to the knob in any desired manner, either by being forced therein whereby sufficient friction is provided to hold the same, or by threading or being made integral therewith.

Pivotedly connected to one end of the lever 30 by the screw 35 is a connection lever 36 having an upwardly turned portion 37 at one end and a finger arm 38 at the opposite end and a stop lug 39 between its ends, 90 which engages the lever 30 and limits the movement of said connection lever 36 in relation to said lever 30.

In operation the device is attached to the 100 inside of a door substantially as shown, and the slightest rotation of the knobs 40 actuates the lever 30 upon its mounting 29 through the chain 32 and spring 33. This movement raises the levers 30 and 36 so that the end portion 37 upon the lever 36, which 105 engages the head 28 of the plunger 27, moves said plunger inwardly and by reason thereof actuates the bell mechanism, which causes the bell to ring and sound the alarm. As soon as the knob 40 is released it returns to 110 its original position, as well as the levers 30 and 36, permitting the plunger 27 to be

moved outwardly and releasing the mechanism and the bell stops ringing.

A stop 44 on the lever 30 contacts with the carrier 15 and limits the movement of the said lever 30 in one direction.

The spring 33 is made slightly heavier than the spring 31 so that upon the first rotation of the knob 40 the spring 33 will not yield, but if a continuous rotation is given 10 to the knob the stop 44 limits the movement of the lever 30, and then the spring 33 yields and permits further movement of the chain 32 without affecting any of the parts with which the spring 33 is connected. Thus 15 the slightest movement of the knob rings the alarm even before the door is opened while the heavier spring 33 accommodates such movement of the knob as is necessary to open the door.

20 Rotation of the knobs 40, will impart no movement to the plunger and the bell will not ring when the lever 36 is moved upon its pivot mounting 35 until it occupies substantially the dotted position shown 25 in Fig. 2, wherein the end portion 37 thereof is moved out of alinement with the head 28.

Of course, wire or other substance may be substituted for the chain 32 if desired and 30 in many ways the details of my invention may be considerably modified without departing from the spirit thereof.

This device is so light, and its bulk so small, and its attachment so convenient, 35 that it may be carried from place to place and attached to doors temporarily, as protection to the room occupant, in which case if no radial post 34 is attached to the knob 40, a substitute can be provided through 40 the clamp 41, having a screw 42 therein which provides means for connecting the chain 32 therewith. This clamp is secured upon the knob of the door through the action of the screw 43, in a well known manner.

45 By manipulation of the nut 17, the relative position of the end 37 of the lever 36 with the plunger 27 may be varied so as to vary the sensitiveness of the device. That 50 is, if the said lever end 37 is in contact with the plunger head 28 when the parts are at rest, the bell will ring upon the slightest movement of the knob, while if it is a slight distance therefrom, sufficient movement of 55 the knob to bring said end in contact, is permissible before the bell will ring and in other ways the adjustment of the carrier is quite desirable. By rotation of the nut, so as to move the carrier to its approximate 60 up position, the relation of the lever 36 and plunger 27 is such that the alarm will continue to sound, if once started until manually released.

65 This device is attached to the door itself and is thus supported, so that its weight is

not upon the door knob, and is therefore much more sensitive in action, and less liable to be discovered by delicate manipulation of the knob to ascertain its presence. Unsuccessful attempts have heretofore been 70 made to accomplish this result, more particularly by supporting the device in the key hole of the lock or lock plate, but this prevents the insertion of the key and hence is very objectionable.

75 Having described my invention, what I claim as new and desire to secure by Letters Patent, is:

1. A burglar alarm comprising a base member fixed relatively to the door knob, 80 having a carrier member adjustable thereon substantially parallel with the door, an alarm bell mounted on said carrier member and actuated through a push mechanism, a lever having a part thereon in contact with 85 said push mechanism and pivotally connected with the carrier member, and an operative connection between the door knob and member, whereby movement of the door knob actuates said push mechanism through 90 the swinging of said lever.

2. A burglar alarm comprising a base member to be separably secured to a door, 95 having a carrier member adjustable thereon, an alarm bell, actuated through a push mechanism, detachably secured to said carrier member, a rock lever pivotally connected with said carrier member and having a part thereon in contact with said push mechanism, and an operative connection between the door knob and said rock lever; 100 said connection being such that a limited rotation of said door knob actuates said alarm mechanism through said rock lever and after placed in operative position, the connection yields in part without imparting further movement to the rock lever.

3. A burglar alarm comprising a base member to be separably secured to a door, 110 having a carrier member adjustable thereon, an alarm bell, actuated through a push mechanism, detachably secured to said carrier member, a rock lever pivotally connected with said carrier member and having a part thereon in contact with said push mechanism, an operative connection between 115 the door knob and said rock lever, said connection being such that a limited rotation of said door knob actuates said alarm mechanism through said rock lever and after placed in operative position, the connection yields in part without imparting further movement to the rock lever, and a member mounted upon said rock lever so as to be movable relatively thereto, and having engagement in one of its positions with said push mechanism.

120 4. A burglar alarm comprising a base member designed to be separably secured to a door, having a carrier member adjustable 125

- thereon, an alarm bell actuated through a push mechanism detachably secured to said carrier, a rock lever pivotally connected with said carrier and having a part thereon 5 in contact with said push mechanism, an operative connection between the door knob and said rock lever, said connection being such that a limited rotation of said knob actuates said alarm mechanism through said 10 rock lever and after placed in operative position said connection yields without imparting further movement to said rock lever; and a yielding connection between one end of said rock lever and said carrier member.
- 15 5. A burglar alarm comprising a base member fixed relatively to the door knob, having a carrier member adjustable relatively thereon, yielding means for resisting the adjustment of said carrier member, a 20 plate connected with said carrier member, an alarm bell actuated through a push mechanism detachably connected with said plate, a rock lever pivotally connected with the said carrier member, having a stop thereon 25 to limit its movement in one direction, a member pivotally connected with said rock lever and movable relatively thereto, and in one of its relative positions actuating said push mechanism during the movement of 30 said rock lever, means for connecting said rock lever with the door knob, actuating said rock lever during the first portion of the rotation of said door knob and yielding during the remainder of said movement.
- 35 6. A burglar alarm comprising a base member fixed relatively to the door knob, having a carrier member adjustable there-
- on substantially parallel with the door, an alarm bell mounted on said carrier member and actuated through a push mechanism, a 40 lever having a part thereon in contact with said push mechanism and pivotally connected with the carrier member, and an operative connection between the door knob and member, whereby movement of the door 45 knob actuates said push mechanism through the swinging of said lever, said connection having a yielding portion and an unyielding portion, the relative strength of said yielding portion being such that it will not 50 yield until said push mechanism has been actuated.
7. A burglar alarm comprising a base member fixed relatively to the door knob, having a carrier member adjustable relatively thereon, yielding means for resisting the adjustment of said carrier member, a 55 plate connected with said carrier member, an alarm bell actuated through a push mechanism detachably connected with said plate, a rock lever pivotally connected with the said carrier member, having a stop thereon 60 to limit its movement in one direction, a member pivotally connected with said rock lever and movable relatively thereto, and in one of its relative positions actuating said 65 push mechanism during the movement of said rock lever, means for limiting the rotation of said member in one direction relatively to said rock lever.
- 70 In testimony whereof, I have hereunto affixed my signature.

MAX GOLDSTONE.
